UNITED STATES PATENT OFFICE.

CHARLES JOSEPH SCHMITT, OF ALGOMA, WISCONSIN.

COMPOSITE TABLE TOP.

Application filed September 13, 1926. Serial No. 135,149.

This invention relates to a composite table top, and has for its object to provide, in a manner as hereinafter set forth, a table top so constructed and arranged as to prevent the accidental skidding, slipping or sliding of the objects supported thereby and further whereby the edges and corners of the top will be prevented from being marred or injured when impacting against an obstruction or when hit by a thrown object or an object carried by a person.

A further object of the invention is to provide a composite table top, in a manner as hereinafter set forth, and consisting of a body portion having fixedly secured therewith in enveloping position with respect to the sides, corners and top thereof, resilient protecting, sound reducing, cushioning and corner reinforcing means acting to prevent the accidental skidding, slipping or sliding of the objects supported by the table top, materially reducing sound caused by game counters or other objects cast or thrown thereon, and further preventing the marring or injuring of the sides and corners of the top.

A further object of the invention is to provide, in a manner as hereinafter set forth, a composite table top including a body portion and a resilient covering therefor extended throughout the upper face of the body portion and banded to the edges of the latter thereby setting up a protecting means for said body portion.

Further objects of the invention is to provide, in a manner as hereinafter set forth, a composite table top which is simple in its construction and arrangement, strong, durable, thoroughly efficient in its use, conveniently assembled, and inexpensive to manufacture.

With the foregoing and other objects in view, the invention consists of the novel construction, combination and arrangement of parts, as hereinafter more specifically described and illustrated in the accompanying drawings, wherein is shown an embodiment of the invention, but it is to be understood that changes, variations and modifications can be resorted to which fall within the scope of the claims hereunto appended.

In the drawings wherein like reference characters denote corresponding parts throughout the several views:

Figure 1 is a perspective view of a composite table top, in accordance with this invention, looking towards the bottom thereof.

Figure 2 is a fragmentary view in section on line 2—2 Figure 1.

Figure 3 is a fragmentary view in section, 60 on line 3—3 Figure 1.

Figure 4 is a vertical sectional view of the top taken on either line 4—4 Figure 1.

Referring to the drawings in detail, 1 generally denotes a composite table top which is of any suitable contour and as illustrated of polygonal shape and formed with rounded corners referred to generally by the reference character 2.

The table top 1 comprises a body portion 3 of any suitable material, preferably wood. The body portion 3 is formed from a single slab of material with the corners thereof squared and further with the corners thereof referred to generally by the reference character 4 inset with respect to the side edges of the body portion 3. The body portion 3 conforms in contour to the shape of the table top other than that the table top when complete is formed with rounded corners and the body portion is set up with squared corners. The side edges of the body portion 3 are indicated at 5, 6, 7 and 8, Figure 1 and each end terminal portion of a side edge is rabbeted as at 9 to provide a seat and a shoulder. The shoulder is indicated at 10. The outer termini of the end terminal portions of the rabbet 9 of one side edge merge into adjacent rabbeted portions 9 of a pair of side edges, or in other words the rabbeted portion 9 of the edge 6 merges into one of the rabbeted portions 9 of the edge 5 and one of the rabbeted portions 9 of the edge 7. The rabbeted portions 9 of the edge 8 merge into one of the rabbeted portions 9 of the edge 5 and one of the rabbeted portions 9 of the edge 7. The rabbeted portions of the edge 5 merge into one of the rabbeted portion 9 of the edge 6 and one of the rabbeted portions 9 of the edge 8 and the rabbeted portions of the edge 7 merge into one of the rabbeted portions 9 of

95

95

100

the edge 6 and one of the rabbeted portions 9 of the edge 8. The merging of the rabbeted portions in the manner as stated provide the squared corners 4 of the body portion 3. The rabbeted portions 9 extend from the lower face of the body portion 3 to the upper face thereof. Each rabbeted portion is rectangular in contour.

Extended throughout the upper face 11 of the body portion 3 is a combined protecting, sound reducing and cushioning element 12 constructed of any suitable resilient material and of appropriate thickness. The element 12 includes a body portion 13 and a lateral flange 14 which is coextensive therewith and of less thickness than the thickness of the body portion 13 and further so disposed whereby the lower face of the flange 15 will be positioned above the upper face of the body portion 3. The providing of the resilient element 12 with the flange 14 forms a vertical shoulder 16 which is coextensive with the body portion 13. The flange 14 is of appropriate width and is formed with a rounded upper face, as indicated at 17. The body portion 13 is of the same thickness throughout and the upper face 17 of the flange 14 merges into the upper face of said body portion 13. The free edge of the flange 14 is substantially feathered as indicated at 18. The body portion 13 of the element 12 corresponds in width and breadth to the width and breadth of the upper face of the body portion 3. The body portion 13 of the element 12 is secured throughout to the upper face 11 of the body portion 3 by a suitable adhesive material, as indicated at 19. The adhesive 19 fixedly secures the body portion 13 to the upper face of the body portion 3 and the shoulder 16 is flush with the side edges of the body portion 3 or rather with that portion of each side edge between a pair of rabbets and is further flush with each of the seats 9. That portion of the flange 14 which is positioned between a pair of rabbets 9, or rather each pair of rabbets 9, is of less width than the remainder of said flange and by this arrangement the intermediate portion of the flange at each side thereof is of less width than the end terminal portions of the flange at such sides. Mounted in each rabbet 9 of a pair is a resilient reinforcing strip of greater height than a side edge of the body portion 3. Each reinforcing strip is flush at its bottom edge with the lower face of the body portion 3 and has its upper edge positioned above the upper face 11 of the body portion 3 and opposes the shoulder 16 and the lower face of a wider portion of the flange 15. The reinforcing strip mounted in one of the rabbets of each pair is indicated at 20 and the reinforcing strip mounted in the other rabbet 9 of the pair is indicated at 21. The strip 20 is of greater length than the strip 21.

The strips 21 have their outer edges abut against the strips 20. The strips 20 are of a length to project from the rabbets in which they are mounted and in a manner so that the inner side faces thereof will abut against the outer end edges of the strips 21, see Figure 1. The outer end edges of the strips 20 are flush with the outer side faces of the strips 21. See Figure 1. The strips 20 and 21 are secured to the body portion 3 by suitable adhesive material indicated at 22, 23 with respect to the strips 20 and at 24, 25 with respect to the strips 21. The strips 20 and 21 are further secured to the body portion 3 by transversely extending hold fast devices 26, 27. The hold fast devices 26 are employed in connection with the strips 20 and the hold fast devices 27 in connection with the strips 21. The hold fast devices 26 preferably are positioned in proximity to the outer ends of the strips 20 and the hold fast devices 27 are positioned in proximity to the inner edges of the strips 21. See Figure 2. The strips 20 and 21 extend above the adhesive material 19 which is employed for securing the body portion 3 to the body portion 13 and the said strips 20 and 21 are secured to the shoulders 16 by a suitable adhesive, indicated at 28 see Figure 3.

Arranged against the portion of each side edge between a pair of rabbets 9 is a combined cushioning and protecting strip 29 formed of suitable resilient material and of the same height as the height of a strip 20 or 21. Each strip 29 opposes a strip 20 and 21 and has its bottom edge flush with the lower face of the body portion 3. The strip 29 has the outer face thereof at each end rounded as at 30 and the curve at one end of one strip forms a continuation of the arc of the curved end of an adjacent strip. The ends of the strips 29 are slightly spaced from each other thereby exposing a portion at the outer end of each of the strips 20 and which is indicated at 31. The exposed portion 31 of a strip 20 forms a continuation of the arc of a pair of opposed rounded ends of the strips 29 see Figures 1 and 2. The upper edges of the strips 29 are flush with the top edges of the strips 20 and 21 and the said upper edges oppose the lower face of the wide and narrow portions of the flange 14. The top edges of the strips 20, 21 and 29 are secured to the lower face of the flange 14 by a suitable adhesive, as indicated at 32. The strips 29 are secured to the side edges of the body portion 3, between each pair of rabbets, by a suitable adhesive as indicated at 33 and the strips 29 are furthermore secured to the strips 20 and 21 by an adhesive material as indicated at 34 and 35.

The strips 29 between each pair of rabbeted portions 9 are furthermore secured to the body portion 3 by a spaced upwardly

extending and inwardly inclined hold fast devices 35 which have their heads countersunk in the bottom edges of the strips 29.

The strips 20, 21 act as a reinforcing means for the corners of the body portion 3 as well as the table top, and further said strips 29 in connection with the strips 20 and 21 set up rounded resilient corners for the table top 1 and further said strips 29 prevent the indenting, marring, or defacing the sides of the table top 1 when such sides meet with an obstruction or hit by other objects. By constructing the element 12, with the flange 14 of less thickness than the thickness of the body portion 13 of said element, and extending the strips to the lower face of the flange 14, it will prevent the possibility of using a sharp instrument to remove the body portion 13 from the bottom portion 3, as such instrument will be prevented from penetrating between the body portion 13 and the body portion 3, in view of the fact that the shoulder 16 will prevent such penetration.

A composite table top, in accordance with this invention is one of long durability, and as it includes a combined protecting, sound reducing, cushioning and reinforcing means, which is constructed of resilient material of the desired thickness, the top is provided with a protecting, sound reducing, cushioning and reinforcing element and which prevents the accidental skidding of slipping of any articles mounted thereon, as well as preventing injury to the body portion of the top when heavy or hot articles are mounted or supported by the element 12. The element 12 also provides means to deaden the noise when game counters are cast or thrown thereon, as the material from which said element is constructed will materially reduce the sound of such game counters when they are cast on the top, will also prevent the counters from slipping and furthermore prevent direct contact thereof with the wooden or other body portion 3. The providing of the body portion 3 at the corners thereof with the resilient strips 20 and 21, in connection with the strip 29, set up cushioned rounded corners enhancing the appearance of the top, and further preventing injury to the corners when they meet with an obstruction. The setting up of the

strips 29 in the manner as shown protect 55 the side edges of the body portion 3 or in other words set up the table top with resilient side edges acting as a protecting medium.

It is thought, that the many advantages 60 of a composite table top, in accordance with this invention can be readily understood, and although the preferred embodiment of the invention is as illustrated and described, yet it is to be understood that changes, 65 variations and modifications can be resorted to which fall within the scope of the invention as claimed.

What I claim is:

1. A composite table top comprising a 70 body portion having a rabbet at each end of each side edge, reinforcing strips secured at each rabbet, protecting strips, each protecting strip secured to a side edge of said body portion and opposing and secured to a pair of reinforcing strips, a cushioning element extended throughout the upper face of and secured to said body portion and opposing and secured with the upper edges of said reinforcing and protecting strips, 75 said reinforcing strips arranged in overlapping relation and said protecting strips having their top and bottom edges flush with the top and bottom edges of the reinforcing strips. 80

2. A composite table top comprising a 90 rigid body portion, a cushioning element extended throughout the top of the latter and secured therewith and further extended from said body portion, protecting strips secured to the sides of said body portion and co-extensive therewith, reinforcing strips interposed between the end terminal portions of said protecting strips and the end terminal portions of the sides of said body portion, means for securing said reinforcing strips to said protecting strips and to said body portion, means for securing said protecting strips to said reinforcing strips and to the 95 extended portion of said element, and said protecting strips having the outer periphery thereof rounded at the ends thereof to provide said table top with rounded cushioned corners. 100

In testimony whereof, I affix my signature hereto.

CHARLES JOSEPH SCHMITT. 105
